J. Gearhart.
Threshing Machine.

Patented Aug. 27, 1835.

Aug. 22. 1835

9053 X 161.

John Gearhardt, Rush, Pennsylvania.

Letters Patent.

The Schedule referred to in these Letters Patent and making part of the same containing a description in the words of the said John Gearhardt himself of his improvement in the machine for threshing grain and seed.

To all to whom these presents shall come.

Be it known that John Gearhardt of Rush in the County of Northumberland and State of Pennsylvania have invented a new and useful improvement in the machine for threshing grain and seed and that the following is a full and exact description of the said improvement. This machine consists of a frame, concaved cylinder, pulley, and the necessary fixtures for putting the whole together. The frame may be made as represented in the drawing or in any other way the mechanic may prefer so as to correspond with the other parts of the machine. Frame two pieces of plank upright (fig 1) into two sills (fig 2) and join them by four girders (fig 3) entering the mortises (fig 4) the concaved (fig 5) is made whole, open back iron or any other material that may be preferred of any desired size, with rows of teeth on the concave surface of such number, shape and size as may be preferred, and is secured on the two upper girders (fig 3) in such a manner as the mechanic may choose. concave beds of different degrees of fineness suited to the grain or seed to be threshed may be used in the same frame by having them so put in as to be removed at pleasure. the cylinder is composed of the shaft (fig 6), the circular pieces (fig 7) which may if preferred be made whole, of the flander (fig 8) and of the pulley (fig 9) and must correspond with, and be made to fit the concaved, one end of the shaft projects beyond the side of the frame to receive the pulley with grooves at each end when it rests on the frame with

with as many circulars upon it as the length may require and holes through it to receive the bolts (fig 8). The circulars if they and the shaft are of wood or metal, may be made together whole, if of wood by turning, if of metal to be cast by running them into, if of metal to be forged by welding them together. The circulars must be of a diameter to correspond with the concave bed with boxes in (fig 10) of any desired number to receive the flanches on their periphery. The flanches made of cast iron or any other material are of a concave form of the same length with the concave bed, of the same circular concavity and of a width and thickness to correspond with the boxes in the circulars on the shaft with teeth on their periphery corresponding with those on the concave bed and holes through them corresponding with those on the shaft, and of a number to correspond with the number of boxes in the circulars. These form the outside of the cylinder and are secured to the circulars by long bolts (fig 12) passing through them and the shaft with a head at one end and a bar at the other. The pulley on the end of the shaft must be of a size to correspond with the circumference of the cylinder the cylinder thus formed is put into the frame and secured by the cap and screw (fig 11) and is put in motion by putting a strap or other fixture upon the pulley and connecting it with any propelling power that may be deemed proper. What I claim as my invention or improvement in the Machine for threshing grain and seed is the mode of constructing concave beds and cylinders as above set forth, the concave bed differs from those of other threshing machines by being whole instead of being in segments and of course is more solid and therefore can be put in or taken out of the frame with much greater facility. The cylinder differs from those of other threshing machines by being open instead of close which gives a much greater proportion of weight to the periphery and consequently greatly increases its force without increasing friction, and is propelled by a less power than the close cylinders; July 10th 1835.
